UNITED STATES PATENT OFFICE.

EDWIN E. BACHMANN, OF BALTIMORE, MARYLAND.

NUT LOCK.

Application filed April 2, 1926. Serial No. 99,293.

My present invention pertains to nut locks of the type in which the nut is keyed to its complementary bolt; and it has for its object the provision of a peculiar and advantageous nut lock of said general type.

To the attainment of the foregoing, the invention consists in the specific improvement hereinafter described and definitely claimed.

In the accompanying drawings, forming part of this specification:

Figure 1 is a view, partly in section and partly in elevation, of a construction embodying one form of my invention.

Figure 2 is a full section of the same.

Figure 3 is a view taken from a view point at the right of Figure 1 and showing the nut and key of my improvement.

Figure 4 is a view taken in the plane indicated by the line 4—4 of Figure 2, and showing the inner side of the novel nut and the manner in which the ends of the U-shaped key are anchored in and to the nut.

Figure 5 is an enlarged perspective of the nut per se.

Figure 6 is a perspective of the U-shaped key per se.

Figure 7 is a view similar to Figure 3 and showing a simplified form of the invention.

Similar numerals designate corresponding parts in Figures 1-6 to which reference will first be made.

Manifestly my novel nut lock may be used to advantage in various relations. I have elected, however, to show the bolt 1 as threaded into a cylinder body 2, and as passed through a cylinder head 3 and equipped on its outer threaded portion with an ordinary nut 4 and my novel nut 5. The bolt 1 is provided in its exposed end portion with crossed diametrical kerfs or slots 6, and the nut 5 is peculiar in that it has a circular series of spaced apertures 7 which extend transversely through it, Figure 2, and in that it is provided with grooves 8 in its face,

Figures 1-3 and 5, and with a circular channel 9 in its inner side. The grooves 8 extend radially outward from the bore of the nut 5 and communicate with the outer ends of the apertures 7; and I would also have it

understood that for reasons of facility in manufacture I prefer to extend said grooves to the outer edge of the nut as illustrated in Figures 1-3 and 5. As shown in Figure 4 the channel 9 is shallow and is in communication with the inner ends of the several apertures 7.

The hereinbefore mentioned key of my improvement is formed in one piece of readily bendable metal or alloy, as designated by 10 in Figure 6, is U-shaped in general configuration, and is provided in its end portions with diametrical bifurcations 11 occupying the center of the longitudinal plane of the key; the mouths of the said bifurcations being flared as designated by 12.

In the practical use of the form thus far described in detail, the nut 5 is turned on the bolt 1 and tight against the face of the bolt 4 or any other abutment that may be present. The key 10 is then inserted so that its legs are sheathed in diametrically opposite apertures 7 of the nut, its cross bar is seated in diametrically opposite grooves 8 of the nut, and in one slot 6 of the bolt, and its ends are opposed to the abutment afforded by the face 70 of the nut 4. The key legs are then forced endwise inwardly in the nut apertures 7, whereupon by virtue of the disposition of the bifurcations 11, and the flared mouths 12 of said bifurcations, the arms 13 of the 80 bifurcations will be upset in opposite directions in the channel 9 and in the direction of the length of said channel, Figure 4, with the result that the key will be strongly anchored of itself in the nut and this with all 85 of the key in the bolt and nut so that the nut and key are strongly held together, and the nut is strongly locked to the bolt and against casual turning to any extent thereon.

A punch applied to the bends of the key 90 in alignment with the key legs may be and preferably is utilized for the described forcing of the key legs endwise inwardly, the punch being subjected to hammer blows or otherwise powerfully applied to the key to 95 bring about the described upsetting of the key ends against an opposed abutment and in the channel 9 of the nut.

Manifestly the plurality of apertures 7 and the plurality of grooves 8 together with the circular channel 9 in the nut, and the crossed slots 6 in the bolt end, lend themselves to nice adjustment of the nut and locking of the nut to the bolt at closely arranged points in the length of the bolt.

The bolt 1^a of the simple and inexpensive embodiment shown in Figure 7 is provided with a single slot 6^a, the key 10^a is identical with the key 10, Figure 6, and the nut 5^a is similar to the nut 5, Figure 5, save that it has no grooves such as 8, its apertures 7^a extending to the face of the nut. In other re-

spects, however, the nut 5^a is like the nut 5, and hence the simplification disclosed in Figure 7 is possessed of the major practical advantages hereinbefore ascribed to the embodiment illustrated in Figures 1-6.

Having described my invention, what I claim and desire to secure by Letters-Patent, is:—

1. In a nut lock and in combination, a threaded bolt with crossed slots in its end portion, a nut having a threaded bore and also having a circular series of spaced apertures about said bore and further having radial grooves in its face and in communication with said bore and apertures and a circular channel in its inner side about the bore and in communication with the inner ends of the apertures, and a U-shaped key of bendable metal having bifurcations in its end portions disposed crosswise of said circular channel and flared mouths at the open ends of the bifurcations, whereby when the key is seated in a coincident bolt slot and nut grooves and the key legs are sheathed in opposite apertures of the nut and the key legs are forced inwardly against an abutment opposed to the inner side of the nut, the arms of said bifurcations will be spread apart and seated in said circular channel to anchor the key legs to and in the nut.
2. In a nut lock and in combination, a threaded bolt with a slotted end portion, a nut having a threaded bore and also having

a circular series of spaced apertures about said bore and further having radial grooves in its face and in communication with said bore and apertures and a circular channel in its inner side about the bore and in communication with the inner ends of the apertures, and a U-shaped key of bendable metal, whereby when the key is seated in the bolt slot and the nut grooves coincident therewith and the key legs are sheathed in opposite apertures of the nut and the key legs are forced inwardly against an abutment opposed to the inner side of the nut, the ends of said legs will be upset in said channel to anchor the legs to and in the nut.

3. In a nut lock and in combination, a threaded bolt with a cross slot in its end portion, a nut having a threaded bore and also having a circular series of spaced apertures about said bore and further having a circular channel in its inner side about said bore and in communication with the inner ends of the apertures, and a U-shaped key of bendable metal, whereby when the key is seated in the bolt slot and the key legs are sheathed in opposite apertures of the nut and the key legs are forced inwardly against an abutment opposed to the inner side of the nut, the ends of said legs will be upset in said channel to anchor the legs to and in the nut.

In testimony whereof, I affix my signature.

EDWIN E. BACHMANN.
